CLAIM

The ornamental design for a partition panel, as shown and described.

DESCRIPTION

FIG. 1 is a perspective view of a partition panel.

FIG. 2 is a front elevation view thereof. A rear elevation view is identical to the front elevation view.

FIG. 3 is a right side elevation view thereof. A left side elevation view is a mirror image of the right side elevation view.

FIG. 4 is a top plan view thereof; and,

FIG. 5 is a bottom plan view thereof.

1 Claim, 5 Drawing Sheets(56)
